GRATE SHAKING MECHANISM FOR FUEL BURNING APPARATUS

Carl H. Holmes, Johnstown, and George F. Geis, Westmont Borough, Pa., assignors to National Radiator Corporation, Johnstown, Pa., a corporation of Maryland

Application July 27, 1937, Serial No. 155,846

5 Claims. (Cl. 126—169)

This invention relates to solid fuel-burning apparatus and is for a mechanism for shaking the grates of such an apparatus. The invention is particularly applicable to hand-fired domestic heating boilers and hot air furnaces.

5 Solid fuel burning appliances frequently embody parallel grate bars mounted at the bottom of the combustion chamber on trunnions for oscillation about their longitudinal axes. Commonly, these grate bars are provided with depending levers, which levers are provided with pins to engage in vertical slots provided in a reciprocating grate-actuating bar. This bar is slidably supported in the base of the fuel-burning apparatus and projects through such base to the front of the furnace where it connects with a lever to which a hand lever is attached. This lever in turn is commonly pivoted on a vertically movable link or fulcrum so that when the lever 10 is rocked back and forth a rectilinear movement will be imparted to the grate-operating bar. By reason of the engagement of the pins on the cranks depending from the grate bars in the slots of the grate-operating bar, such rectilinear movement is translated into a rocking motion of the grates. Such constructions, while commonly employed, require a great number of parts in the form of attachments, and are objectionable from the standpoint of design and appearance. Moreover, the manner of transmitting motion from the lever to the grates is inefficient and frequently requires considerable force in operating the grates.

35 The present invention provides a grate-operating mechanism wherein all movable parts except the operating extension of the hand lever are located entirely within the base of the fuel-burning apparatus, and in which the motion of the hand lever is transmitted to the grate bars in a smooth and efficient manner, enabling the grate bars to be operated much more easily and smoothly than in the structures heretofore provided and with less noise.

45 The invention also provides a more convenient arrangement than has been heretofore available for normally holding the hand lever against movement and for limiting the extent of the rocking movement of the hand lever, and which also permits the lever to be moved when desired to a position where the grates can be completely dumped.

50 The invention may be readily understood by reference to the accompanying drawings, in which:

55 Figure 1 represents a transverse vertical sec-

tion through the lower portion of a fuel-burning apparatus embodying our invention;

Figure 2 is a horizontal section in the plane of the staggered line II—II of Figure 1;

Figure 3 is a fragmentary sectional view of the support for the rocking lever.

Referring to the drawings, 2 and 3 designate two parallel grate bars of more or less conventional form supported at the bottom of a firebox 4 in any usual or preferred way so as to rock about 10 their longitudinal axes, the centers of rotation of the grate bars being designated c. The grate bars themselves and the manner of supporting them in the firebox form no part of the present invention, any conventional arrangement being utilized. Each grate bar is provided with a downwardly extending arm 5, which arm is provided at its lower end with a laterally offset pin or projection 6. While the drawings illustrate only two grate bars 2 and 3, there may be any usual 20 number of them, depending on the size and capacity of the fuel-burning apparatus, two being the minimum number of bars employed and serving to adequately illustrate our invention. The fuel-burning apparatus is supported on an enclosing base structure having a rear panel 7, a side panel 8 and a front panel 9, the front panel, of course, being provided with the usual ash door 10. The projections or trunnions 6 on the crank arms 5 depending from the grate bars pass 30 through openings 11 in a grate-operating bar 11, the openings 11 being sufficiently large to provide a free working fit for the projections 6 therein. The forward end of the grate-operating bar 11 is sloped downwardly, this downwardly 35 inclined portion being designated 12, and it has a terminal portion 13 in which is a hole 14. Cast integrally with the front panel 9 on the inside of the base are inwardly extending brackets 15 between which extends a supporting pivot 16, 40 this preferably also being cast integrally with the base. The front panel 9 to the side of the ash door is provided with a vertical slot-like opening 17. There is provided an external operating lever 18 having an offset lower portion 45 which projects through this slot 17, there being a downwardly extending arm 19 on this offset portion and an integral hook-like bearing 20 that engages over the cross pin or support 16. The lower end of the arm 19 has a transverse pin 50 or projection 21 preferably formed integrally thereon, this pin projecting through the hole 14 in the terminal portion 13 of the grate-operating bar. A cotter pin 22 serves to keep the pin 21 and the end of the grate-operating bar from lat-

eral displacement. An abutment such as the projection 23 on the rear panel of the base serves to prevent lateral displacement of the grate-operating bar off the projections 6 of the crank arms 5 on the grates. Assembly of the parts as thus provided can be very simply and quickly made.

The supporting member 16 is below the level of the centers of rotation *c* of the rate bars 2 and 10 3 a distance substantially equal to the distance which the terminal of the grate-operating bar is inclined downwardly. *c'* represents the centers of the pins or projections 6 on the crank arms 5. *d* represents the center of the bearing member 16, this 15 being the center about which the lever 18 rocks. The center of the projection 21 on the lower end of the lever is marked *d'*. The distance between the centers *d* and *d'* and *c* and *c'* is substantially the same. Therefore, when the lever 18 is 20 rocked on its support 16, the projection 19 with its pin 21 and the crank arms 5 on the grates with their projections 6 remain substantially parallel and swing through corresponding arcs about equal radii. When the lever 18 is pulled to the 25 left as viewed in Figure 1, the grate-operating bar 11 moves to the right and also lifts upwardly. The weight of the grate-operating bar is suspended entirely from the grates and the end of the lever 18. Consequently, rocking of the 30 lever toward the left as viewed in Figure 1, lifts the grate-operating bar 11, as well as moving it to the right, which counterbalances to a considerable extent the weight of the lever. When the lever 18 is moved in the reverse direction, i. e., 35 toward the right as viewed in Figure 1, the weight of the grate bar returning to its normal position tends to restore the grates to their normal position and again counterbalance the movement of the lever.

40 The whole arrangement not only provides for a very smooth and free operation of the grates, and by reason of this counterbalancing action makes the operation of the grates easier, and less effort is required to overcome the friction between various parts than has been the case with grate-operating mechanisms heretofore provided. The 45 offsetting of the lower end of the lever 18 and supporting it inside the base of the fuel-burning unit not only simplifies the general construction, but allows the grate-operating lever 18 in its normal position to stand close against the front wall of the furnace and not project out into the 50 room as do the levers on the various grate-operating mechanisms now generally provided. This 55 makes a more compact structure and it eliminates any requirement for a removable shaking lever such as is now generally used, because of the fact that the lever does extend so far to the front of the furnace. Moreover, the offset arrangement 60 of the lever more effectively counterbalances the weight of the grate-operating bar 11.

The upper end of the lever 18 may have a forwardly projecting handle 18a as best shown in Figures 5 and 6, so that while the lever normally 65 is close against the front of the furnace or boiler, it can nevertheless be very conveniently grasped.

The advantages of the invention reside, among other things, in the compactness and cheapness of the structure, its neat appearance, and in the fact that the operating lever is normally close to the front of the boiler or furnace structure, and does not project out into the room. The suspension of the grate-operating bar 11 from the cranks 5 and from the lower terminal of the lever 70 75 18 in such manner that this bar has a curvilinear

motion along with the lever and with the cranks on the grate bars, makes an effective linkage which is free-operating and in which the grate-operating bar 11 is not only effective for transmitting motion to the grate bars, but serves also as a counterweight. The offset portion of the handle substantially closes the opening in the panel through which it extends.

While we have shown and described one specific embodiment of our invention, it will be understood that this is by way of illustration and not by way of limitation, and that various changes and modifications may be made therein.

We claim:

1. Fuel-burning apparatus comprising an enclosing structure having a base and having tilt-able grates, each grate being provided with an operating crank thereon, said base having a slotted front panel and having a bearing pin on the interior thereof adjacent the slot, an operat- 15 ing lever having an exposed upper portion acces- 20 sible at the exterior of the structure and having an offset lower portion which projects through the slot and has an offset bearing intermediate the ends of the lever to engage said bearing 25 pin, the lever having a lower terminal portion below the bearing, a grate-operating bar pivotally hung from said terminal portion of the lever and from the operating cranks on the grate, the 30 cranks having pins thereon which pass through the bar, and an abutment on the interior of the base to prevent lateral displacement of the bar and prevent the bar from accidentally becoming disengaged from said pins.

2. Fuel-burning apparatus comprising an enclosing structure having a base and having tilt-able grates, a grate-shaking lever for operating said grates, said lever having a portion which ex- 35 tends upwardly along the outside of the front of the structure, and having a lower portion which 40 normally extends downwardly inside the base, the base being slotted where the lever passes therethrough, the portion of the lever passing through the slot normally filling and closing the 45 slot, and means on the base adjacent the slot providing a pivotal support for said lever.

3. Fuel-burning apparatus, comprising a fur- 50 nace structure having a base, tilttable grates in the structure, a lever for operating the grates, said base having a slot therein, said lever having an offset portion intermediate its ends which 55 normally closes the slot, the portion of the lever above the said offset portion normally extending upwardly generally parallel to the front of said structure, the portion of said lever below said offset portion being inside the base, and means on the inside of the base adjacent to the slot for pivotally supporting said lever.

4. Fuel-burning apparatus comprising an enclosing structure having a base, tilttable grate 60 bars in the base having depending crank arms thereon, an operating lever pivotally supported between its ends on the base with the lowermost end of said lever inside the base and the upper portion thereof outside the base, and a grate-operating bar pivotally engaging the lower end of the lever and pivotally engaging the crank arms 65 on the grate, the base having a vertical slot therein through which the lever passes, the lever having a diagonally offset portion positioned within the slot and normally closing the same, throughout the length and width of the slot to thereby exclude the flow of air through the slot, and whereby the portion of the lever above the 70 75

offset is normally close to the front of the enclosing structure.

5. Fuel burning apparatus comprising an enclosing structure having a base and having tiltable grates, a grate-shaking lever for operating said grates, said lever having a portion which extends upwardly along the outside of the front of the structure, and having a lower portion which normally extends downwardly inside the base,

the base being slotted where the lever passes therethrough, the portion of the lever passing through the slot normally closing the slot, and means on the base adjacent the slot providing a pivotal support for said lever, the lever permitting 5 tilting of the grates in one direction only from a normal position.
